UNITED STATES PATENT OFFICE.

RICHARD M. MURPHY, OF EASTHAMPTON, MASSACHUSETTS.

ICE-CREEPER.

1,132,787.

Specification of Letters Patent.

Patented May 9, 1916.

Application filed March 25, 1915. Serial No. 16,950.

To all whom it may concern:

Be it known that I, RICHARD M. MURPHY, a citizen of the United States, residing at Easthampton, in the county of Hampshire and State of Massachusetts, have invented 5 certain new and useful Improvements in Ice-Creepers; and I do hereby declare the following to be a full, clear, and exact description of the invention, such as will enable others skilled in the art to which it 10 pertains to make and use the same.

This invention relates to ice creepers.

One of the objects of this invention is to provide an improved ice creeper, which may 15 be worn as an entirety upon the heel and sole of a shoe, or the same may be dissected and either the heel or the sole portion of the creeper worn if so desired.

Another object of this invention is to 20 provide an ice creeper which is capable of both longitudinal and lateral adjustment for adapting the same to shoes of different sizes.

Another object of this invention resides in 25 the novel construction of the calks used upon the ice creeper, wherein the same are capable of being readily attached to or detached from the body of the creeper for replacing the calks when the same have 30 become worn.

A further object of this invention is to provide an ice creeper which is neat in appearance, of simple construction, and practically inexpensive to manufacture.

These and other objects will more fully 35 appear as the nature of the invention is more clearly understood from the following specification, the subject matter of the claim, and the illustrations in the accompanying drawings, in which,

Figure 1 is a side elevation of the invention showing the same as applied to a shoe. Fig. 2 is a bottom plan view of the invention, showing the novel means to provide for 45 the longitudinal and lateral adjustments, and the means for dissecting the ice creeper when desired. Fig. 3 is a detail sectional view, on line 3—3 of Fig. 2, of one of the calks forming part of the invention, showing 50 the novel manner of securing the calks in operative position upon the body of the device.

Referring the drawings, the forward section or sole portion of the ice creeper consists of the toe plate 1, the side bars 2 terminating in the upwardly and rearwardly

connecting arms 3, the side bars 2 and connecting arms 3 being reinforced by the brace bar 4. This front section is constructed of a conformation for fitting the under surface 60 of the sole and a portion of the instep of a shoe, and for securing the front section to the sole of a shoe, the straps 5, or other securing means, are provided. These straps have one or their ends secured to the bars 65 2 at a point adjacent the toe plate 1 by means of the rivets 6, or other suitable securing means. The straps 5 pass upwardly through the upwardly and outwardly extending loops 7 formed upon the outer 70 edges of the side bars 2, and the free ends of the straps 5 are then brought over the toe of the shoe and secured together by means of the buckle 8, or other suitable fastening means. 75

The rear section of the ice creeper consists of a heel plate divided longitudinally to provide the segments 9 and 10, each provided with the marginal upstanding flange 11. The upper central portions of the 80 flanges 11 are provided with the outturned loops 12 in which are secured one end 13 of the straps 14, or other suitable securing means. The free ends of the straps 14 are passed upwardly over the instep of the shoe 85 of the user, and secured together through the medium of the buckle 15, or other suitable securing means, for holding the rear section of the creeper securely upon the heel of a shoe. 90

The segment 9 of the heel plate is provided with the laterally extending tongue 16 projecting from the enlarged offset portion 17 having the elongated slot 18 formed therein. The segment 9 is further provided with the elongated slot 20 which extends from a point in proximity to the slot 18 transversely across the segment 9 toward the opposite side. The segment 10 is provided with the laterally extending tongue 21 in 100 the plane of the segment 10, and projects through the slot 18 of the offset 17 of the segment 9. The segment 10 is also provided with the transversely arranged elongated slot 22 corresponding to the slot 20 of the segment 9. Each of the ends of the tongues 16 and 21 are provided with an aperture, and passing through these apertures and the respective slots 20 and 22 of the segments 9 and 10 are the securing bolts 23. The bolts 110 23 are adapted to be loosened and are then capable of sliding movement in the slots 20

and 22 of the respective segments 9 and 10. This arrangement provides for the ready lateral adjustment of the heel plate for fitting the same to heels of different sizes, and after 5 the desired adjustment, the bolts 23 are then tightened to bind the overlapping tongues 16 and 21 firmly against the under surfaces of the segments 10 and 9 respectively and thus fixedly secure the segments 9 and 10 in 10 their laterally adjusted positions.

The forward portions 24 of the segments 9 and 10 are each provided with the elongated longitudinally extending slots 25, to provide for the longitudinal adjustment of 15 the rear section of the ice creeper relative to the front section, to adapt the device to shoes of different lengths, which is accomplished by the adjustment of certain of the calks, to be hereinafter described, which 20 calks project through the slots 25 and the apertured ends 26 of the substantially Z-shaped connecting bars 27. The connecting bars 27 attachably and detachably connect the front and rear sections so that either or 25 both sections may be used, the forward ends of the connecting bars 27 being provided with apertures for registering with the apertures in the ends of the arms 3 of the front section, and passing through these apertures 30 are the bolts 28 for securing the front and rear sections of the device together.

The calks constituting part of this invention, as shown in detail in Fig. 3, are constructed with the enlarged flattened head 29, 35 the screw threaded shank 30 terminating in the sharp pointed end 31. In attaching these calks to the respective sections of the device the same are passed through apertures formed in the respective front and rear 40 sections with the head 29 resting upon the upper surfaces of the sections, and afterward screwing the nut 32 upon the threaded shank 30 securely against the under surfaces of the sections, whereby the calks will be effi- 45 ciently secured upon the respective sections of the creeper. It will thus be seen, that when the calks have become unfit for use by wear, the dull calks may be readily removed by unscrewing the nut 32 with a 50 suitable wrench, removing the dull calks, and readily replacing the same with newer and sharper calks. A greater or lesser number of calks may be used than those illustrated in the drawings if so desired, this being 55 accomplished by either reducing or increasing the number of apertures in the body portions of the device for the introduction of the calks.

From the foregoing description of the 60 invention and the illustrations in the accompanying drawings, it will be seen that I have provided an ice creeper which is capable of being used as a unitary structure for engaging the entire heel and sole construction of a shoe, or if so desired the same

may be dissected by removing the bolts 28 which secure the front and rear sections together, and in this event either the sole portion of the device or the heel portion may be used as desired. Furthermore, that by 70 the provision of the overlapping tongues 16 and 21, and the securing bolts 23, the rear section of the device may be adjusted laterally to fit heels of different widths, and maintained in fixed adjusted position by 75 the tightening of the securing bolt 23. Another advantageous feature resides in the provision of the elongated longitudinally extending slots 25 formed in the forward portions of the segments 9 and 10 of the 80 rear section of the device, whereby when the device is used as a unitary structure the sections may be adjusted longitudinally with respect to each other for adapting the device to shoes of different lengths, this being accomplished by loosening the nuts 32 of the two calks 31, which calks in this instance not only perform the function of anti-slipping devices but also as adjusting bolts, and sliding the shanks 30 thereof in the desired direction within the slots 25, and subsequently tightening the nuts 32 of the calks for binding the ends 26 of the connecting bars 27 against the upper surfaces of the segments 9 and 10 for securely retaining the 95 front and rear sections of the device in adjusted relation.

While I have here shown the preferred embodiment of my invention, I may make such minor alterations and variations therein from time to time as I may deem expedient without departing from the spirit of this invention and the scope of the appended claim.

Having described my invention, what I 105 claim as new and desire to secure by Letters Patent, is:—

An ice creeper, comprising a front section shaped to conform to the sole of a shoe and provided with rearwardly and upwardly extending arms bent to conform to and engage a portion of the instep of the shoe, a rear section for engaging the heel of the shoe consisting of two members laterally adjustable with respect to each other and provided with forwardly directed extensions provided with elongated longitudinally directed slots, interconnecting members interposed between the rearwardly extending arms of said front section and the forwardly directed 110 extensions of the members of said rear section, said interconnecting members consisting of vertical central portions for engaging the forward side of the heel, upper and forwardly extending arms bent to conform to the curvature of the instep of the shoe and having their ends detachably connected to the respective arms of said front section, and lower and rearwardly extending arms carrying bolts for seating in the 115 120 125 130

respective slots of the forward extensions of the members of said rear section for detachably and adjustably connecting the rearwardly extending arms of said interconnecting members to said rear section, and means upon each of said sections for securing said sections upon a shoe.

In testimony whereof I have signed my name to this specification in the presence of two subscribing witnesses.

RICHARD M. MURPHY.
